UNITED STATES PATENT OFFICE.

VIRGIL H. SNOOK, OF AURORA, ILLINOIS.

CARPET-SWEEPER.

SPECIFICATION forming part of Letters Patent No. 271,284, dated January 30, 1883.

Application filed February 9, 1882. (No model.)

To all whom it may concern:

Be it known that I, VIRGIL H. SNOOK, of Aurora, in the county of Kane and State of Illinois, have invented certain new and useful Improvements in Carpet-Sweepers; and I do hereby declare that the following is a full, clear, and exact description of the invention, which will enable others skilled in the art to which it appertains to make and use the same, reference being had to the accompanying drawings, and to the letters of reference marked thereon, which form a part of this specification.

My invention is an improved duplex and reversible machine that is simple in construction, capacious, readily adjusted and cleaned, not liable to get out of order, and efficient and noiseless in operation.

It consists in arranging and combining in a case having a handle and a supporting-wheel at each of its four corners, and a partition in its top and center two rotating brushes having adjustable bearings and friction-wheels on the ends of their journals, a single detachable tray, and two dirt-conveying tracks, as hereinafter fully set forth.

Heretofore two rotary brushes have been combined with and operated in a case having four supporting drive-wheels at its corners in such a manner as to gather and deposit dirt in separate detachable trays at the ends of the case. Two rotary brushes, connected by pulleys and belts, have also been combined with and operated in a case having supporting drive-wheels at one end only in such a manner as to gather dirt and deposit it in a duplex tray located between the two brushes. A dirt-conveying track has also been used in a case having but one rotating brush to adapt it to be used as a reversible sweeper; but in the use of separate dirt receptacles or trays at each end of the case, it takes much more time and labor to detach, remove, empty, and replace the two trays than only one, as contemplated by my invention; and in the instance where one duplex tray has been placed between the two brushes connected by pulleys and belts, the brushes always rotate toward each other, and the dirt partially lifted and left on or near the surface of the nap of the carpet by the brush in advance is brushed downward and into the nap, and meshes of the carpet again by the reverse or counteraction

of the second brush. By my manner of construction, arrangement, and combination of the several elements and sub-combination the two rotating brushes are made to rotate independently of each other, but always in the same direction relative to each other to always brush the carpet and dirt in the direction the machine is moved, and at the same time carry the dirt picked up by the separate brushes into one and the same single detachable tray located between the parallel brushes.

Figure 1 of my accompanying drawings is a perspective view of my machine with a part of the case broken away. Fig. 2 is a bottom view. Fig. 3 is an end view. Fig. 4 is a transverse sectional view. Fig. 5 is a perspective of my detachable tray. Fig. 6 is a top view of an adjustable plate and bearing for the journals of the revolving brushes. Fig. 7 is a perspective view of a plate and stub-axle adapted to be adjustably connected with the case to receive the supporting drive-wheels. Jointly considered, these figures clearly illustrate the construction, operation, and utility of my complete invention.

A represents a case of quadrangular form. It is open at its bottom, and has a cover or roof that inclines downward, in opposite directions from its center, over the brushes in the ends of the case. The case is preferably made of wood and sheet metal combined, and may vary in size, as desired. a (shown in Fig. 7) is a flat metal plate, having a stub-axle, b, formed integral therewith or fixed thereto, and two slots, 1 2, adapting it to be adjustably fastened against the outside corner of the case by means of clamping-screws c, to receive a wheel, B. By thus attaching a wheel at each corner the case is elevated and supported upon traveling wheels that also serve as drive-wheels to actuate revolving brushes: a' (shown in Figs. 1, 3, and 6) is a flat metal plate and journal-bearing, having slots 3 4, adapting it to be adjustably connected with the sides of the case to support revolving brushes F in such positions relative to the wheels B that friction-pulleys d, fixed to the ends of the shaft-journals, will engage the peripheries of the wheels B, and transmit motion from the wheels B to the brushes F in such a manner as to cause the brushes to revolve in opposite directions from the wheels, but in the same direction rela-

tive to each other, as required to brush the nap of the carpet and the dirt in the same direction and carry and deposit it into the tray located between the two brushes during the reverse or back and forth movements of the complete machine.

5 G is a handle that has a forked shank, adapting it to be pivoted to the top and center portions of the case A, so that it can be turned over the case at pleasure to advance the machine in any direction by pulling or pushing.

H is my detachable tray, preferably made of sheet metal. It corresponds in length with the inside of the case A and in width with the space between the two revolving brushes F.

15 It has a closed bottom, vertical ends, and inwardly-inclined sides k, over which dirt is delivered from the revolving brushes on its opposite sides. The one end, f, has a perforation, f', adapting it to be suspended upon a pin, m, fixed to one of the sides of the case to project inward, as clearly shown in Figs. 1 and 4. g is a loop fixed to the opposite end of the case to project outward through a slot in the case, and to be engaged by a hook, h, pivoted to the outside of the case, for the purpose of detachably fastening the tray in the case. f'' is a notch in the top and center of the end f of the tray, adapting it to engage the central partition and dirt-directing guide I, fixed in the top and center of the case, as clearly shown in Figs. 1 and 4. Vacant spaces L occur between the lower portions of the inclined sides k of the detachable tray H and the revolving brushes, through which dust and dirt lifted from the floor or carpet are drawn upward by the motions of the brushes and the currents of air that result from the actions of the brushes when the brushes revolve toward the inclined sides 40 of the tray.

20 r (shown clearly in Figs. 1 and 2) are journal-guards in the form of continuous rows of bristles fixed in the ends of the rotating brushes F in such a manner that they will brush against the sides of the case A and prevent carpet ravelings or threads and obstructions from coming in contact with and adhering to the journals of the rollers. Bunches of bristles at distances apart on the ends of rotating 45 brushes have revolved in contact with the inside of a case, but threads were not thereby prevented from passing between the bunches to wrap upon the journals, as contemplated by my continuous circumferential guards.

25 s s (clearly shown in Fig. 4) are sheet-metal plates fixed in the ends of the case A in such positions relative to the brushes F that their

central portions will be concentric with the revolving brushes, and their ends eccentric to the same brushes, to form tracks upon which 60 dirt that is drawn into the open spaces L' at the bottom is elevated and carried over the brushes to fall into the tray H, located between the brushes. In lieu of the metal plates s, the inside faces of the wooden end pieces of the case 65 A may be made concave to perform the same function.

From the foregoing detailed description of the construction and function of each part of my machine their unitary actions and the 70 practical operation of my complete invention is obvious—

I claim as my invention—

1. In a carpet-sweeping machine, the arrangement and combination of a case supported upon wheels at its corners, and having a dirt-directing concave and track at each end, two rotating brushes having adjustable bearings and friction-wheels at their ends, and a detachable tray adapted to be placed between the two 80 brushes, substantially as shown and described, to operate in the manner set forth, for the purposes specified.

2. The detachable tray H, having inclined sides k and fastening devices on its vertical 85 ends, in combination with a case, A, having a partition, I, in its top and center, and revolving brushes on opposite sides of said partition, substantially as shown and described, to operate in the manner set forth, for the purposes 90 specified.

3. The detachable tray H, having a perforation, f', and notch f'', in one of its vertical ends, and a loop, g, at its opposite end, in combination with a case, A, having a fixed pin, 95 m, a fixed partition, I, an opening to admit the loop g, and a hook, h, to engage the said loop, substantially as and for the purposes specified.

4. The duplex and reversible sweeping machine composed of the following elements, to-wit: the case A, having wheels B at its corners, and a handle, G, the revolving and adjustable brushes F, having fixed friction-pulleys d and elastic guards r on their ends, the 100 fixed dirt-guard and partition I, the concave tracks or case ends s, and the detachable tray H, substantially as shown and described, to operate in the manner set forth.
